G. C. LARAIA,
BARBER CHAIR.
APPLICATION FILED MAY 1, 1917.

1,334,157.

Patented Mar. 16, 1920.

Fig. 1. III

UNITED STATES PATENT OFFICE.

GIUSEPPE CARMELO LARAIA, OF NEW YORK, N. Y.

BARBER-CHAIR.

1,334,157.

Specification of Letters Patent. Patented Mar. 16, 1920.

Application filed May 1, 1917. Serial No. 165,650.

To all whom it may concern:

Be it known that I, GIUSEPPE CARMELO LARAIA, a citizen of the United States of America, residing in the borough of Manhattan, city, county, and State of New York, have invented certain new and useful Improvements in Barber-Chairs of which the following is a specification.

This invention relates to improvements in 10 barber chairs or the like.

The invention provides improved means for locking and unlocking the chair against 15 pivotal movement and improved means for locking and unlocking the reclinable back and foot rest.

The invention further provides improvements in the base construction.

Other features of improvement will be hereinafter pointed out.

20 In the accompanying drawings the invention is shown as embodied in a chair with a reclinable back and foot-rest (not shown) which may be held in adjusted position by means of a rod.

25 Referring to the drawings,—

Figure 1 illustrates so much of a barber chair as is necessary to disclose the invention, the figure being a vertical sectional view;

30 Fig. 2 is a horizontal section on the line II—II in Fig. 1, (parts of the base being omitted);

Fig. 3 is a vertical section on the line III—III in Fig. 1;

35 Fig. 4 is a horizontal section through the clamp at the upper part of Fig. 1;

Fig. 5 is a detail view of a part of the cams 74 and 75 shown in Fig. 4;

40 Fig. 6 is a horizontal sectional view of a second embodiment of the clamp for the rod connected to the reclinable back and foot rest.

45 Referring to Figs. 1 to 5 of the drawings, numeral 1 designates a column adapted to support at its upper end the seat of a barber chair or the like, and rotatably fitting within a cylinder 2. The lower end of the column 1 may rest upon a pivot 3 in the lower part 50 of the cylinder 2. The cylinder 2 preferably rests upon a base-plate 4, a projection 5 and recess 6 being provided between the cylinder 2 and base-plate 4 to prevent relative rotation of the parts.

55 The base preferably also comprises a base 9 molding 7, a barrel portion 8, and a cap 9

resting on the barrel portion. The barrel portion 8, molding 7 and base-plate 4 are fastened together by a tie piece 10. This tie piece 10 is preferably formed of malleable iron, has headed portions 11 which fit 60 over lugs 12 upon the barrel portion 8, and has foot portions 13 which are fastened to the base-plate 4 by suitable means, such as bolts 15. The tie piece 10 acts as a resilient fastener, inasmuch as the foot pieces 13 are 65 formed so as not to fit against the base-plate 4 except when strongly pulled thereagainst by the bolts 15. The barrel portion 8 has shoulders 17 which fit over shoulders 18 on the cylinder 2, and hence hold the cylinder 70 2 connected to the base-plate 4. A tooth and notch connection 20, 21 prevents turning of the barrel and cylinder.

To lock the column 1 against turning in the cylinder 2, clamp blocks 22, 22 are provided. These clamp blocks have fulcrum portions 23 and bearing portions 24 adapted to bear against the cylinder 2. A screw-piece 26 threaded in the column 1 has a head 27 which bears against the clamp blocks 22, 22 and presses them into clamping engagement with the cylinder 2. Connected to the screw-piece 26 is a rock arm 30. To one arm of the rock arm 30 is connected a link 31, the link 31 being connected at its upper end to a lever 32. 34 designates a projection adapted to be rocked into contact with the lever 32 to depress it and the link 31, thereby to rock the arm 30 in a direction to turn the screw-piece 26 in 85 a direction to loosen the clamp pieces 22 from against the cylinder 2. The lever 32 preferably has a notch 35 therein in which the projection 34 may rest so as to hold the link 31 depressed and the parts of the 90 clamps hence maintained in loosened position.

The projection 34 is preferably mounted upon a rock shaft 45 to which may be attached a suitable handle. 100

In order to advance the action of the projection 34 on the lever 32 when the handle is turned, the projection 34 is preferably adjustable around the axis of the shaft 45. For this purpose the projection 34 may be 105 formed as a separate piece 42 having a notch connection with the end of the shaft 45, or with a part 74 fixed on the end of the shaft 45. A screw-bolt 43 may be provided for holding the parts 42 and 74 together. 110

At the side of the rock arm 30 opposite the link 31 is connected a pivoted abutment 37 against which bears a spring 38. The other end of the spring 38 bears against a sleeve 39 which is preferably threaded in a projection 40 of the column 1, and the spring 38 presses the rock arm 30 in a direction to turn the screw-piece 26 in a direction to press the clamp pieces 22 into binding engagement against the cylinder 2. When the lever 32 and link 31 are not pressed down by the projection 34, the spring 38 is free to exert a pressure against the abutment 37 and rock the screw-piece 26 so as to press the clamp pieces 22 into combined engagement against the cylinder 2. The tension of the spring 38 may be adjusted by the threaded sleeve 39. The threaded sleeve 39 may be locked in place by a set screw 41.

50 designates a rod which is attached to a reclinable back and foot rest of usual construction. Such a reclinable back and foot rest is illustrated in my application Serial No. 10,907, filed February 27, 1915. The rod 50 is held in its adjusted positions by means of a clamp 51. The clamp 51 comprises a pair of sleeves 52, 53, one or both of which may be threaded into the column 1, preferably, as illustrated, through the intermediary of threaded bushings 54, 55. Around the ends of the bushings 54, 55 is preferably a sleeve 56 having openings 57 through which the rod 50 passes. The sleeve 56 acts as a guide for the rod 50. The inner end of the sleeve 53 is preferably sharpened, as indicated at 58 and is adapted to coöperate with a clamping piece 60 to bite the rod 50 and hold it in adjusted position. The clamping piece 60 is slidably mounted within the sleeves 52, 53 and is normally pressed into biting engagement with the rod 50 by means of a spring 61 between two followers 62, 63. A screw 64 may be provided for adjusting the tension of the spring 61. The tension of the spring may also be adjusted by turning the sleeve 52 in the bushing 54. The sleeve 53 may be turned in its bushing 55 in order to bring new portions of its edge 58 in position against the rod 50, when portions of the edge 58 become dulled or worn. Set screws 59 may be provided for locking the sleeves 52 and 53 against turning. In order to loosen the bite of the clamping piece 60 on the rod 50, a lever 70 and slide rod 71 are provided. The lever 70 is connected to a sleeve 72 loose upon the shaft 45 and pivoted to a collar 121 swiveled on the sleeve 53. A collar 73 fast upon the shaft 45 bears against one side of the sleeve 72. On the inner end of the shaft 45 is fixed a cam piece 74 and this cam piece bears against a corresponding cam piece 75 on the column 1.

65 1. In rocking the shaft 45 in the proper di-

rection the cams 74 and 75 cause the shaft 45 to be pulled inward. The inward movement of the shaft 45 is transmitted by the collar 73 to the sleeve 72, and the sleeve 72 moves the lever 70 and slide rod 71 inward, causing the clamp block 60 to be pressed inward against pressure of the spring 61 thereby releasing the rod 50. In this position the reclinable back and foot rest may be adjusted. A spring 77 may be provided for pressing the sleeve 72 against the collar 73 and for maintaining the parts in normal position.

It will be perceived that when the rock shaft 45 is turned in one direction the cams 74 and 75 operate to pull the rock shaft 45 inward and release the clamp block 60, as just described, the projection 34 being at the same time moved upward or in a direction opposite to that in which it moves to depress the lever 32 and parts connected therewith for releasing the clamp for locking the column against turning in the cylinder 2. When the shaft 45 is turned in the opposite direction to that just referred to the projection 34 is brought into contact with the lever 32 and depresses the same to release the clamping parts 22 from binding contact with the casing 2, the cams 74 and 75 being inactive to draw the rod 45 inward and consequently not affecting the bite of the clamp block 60 upon the rod 50.

To limit the degree of turning of the shaft 45, shoulders 80, 81 may be provided upon the cam pieces 74 and 75, as illustrated in Fig. 5.

In Fig. 6 a second embodiment of clamp for the rod connected to the reclinable back and foot rest is shown.

107 designates said rod connected to the reclinable back and foot rest. 108 designates a clamp for holding the rod 107 in adjusted position.

The clamp 108 preferably comprises two screw-threaded sleeves 109 and 110. These sleeves 109 and 110 are preferably screw-threaded into bushings 111 and 112 fixed to the seat supporting part or column 1. Around the bushings there is a rotatable sleeve 113 which acts as a guide for the rod 107. Within the sleeves 109 and 110 is a sliding locking piece 115 having a tooth 116 fitting within notches 117 formed upon the rod 107. The tooth 116 upon the locking part 115 is pressed into engagement with the notches 117 of the rod 107 by a spring 61 between two followers 62 and 63. A screw 64 may be provided for adjusting the tension of the spring 61. The tension of the spring may also be adjusted by turning the sleeve 110. The locking part 115 may be pushed inward to release the tooth 116 from the notches 117 by means of the lever 70 and the sliding rod 71.

130 By turning the sleeve 109 in the bushing 110

111 the amount of movement of the lever 70, and consequently the amount of movement of the rod 71, necessary to operate the clamp, to release the rod 107, may be adjusted.

Variations may be made in the constructions herein specifically illustrated and described without departing from the spirit of the invention.

10 What I claim is:—

1. A barber chair comprising a seat supporting part, a cylinder in which said seat supporting part is rotatably mounted, a clamp for fixing said seat supporting part against rotation in said cylinder, and means for operating said clamp, said clamp comprising a rock arm and a screw-shaft operated by said rock arm.

2. A barber chair comprising a seat supporting part, a cylinder in which said seat supporting part is rotatably mounted, a clamp for fixing said seat supporting part against rotation in said cylinder, means for operating said clamp, said clamp comprising a rock arm, a screw shaft operated by said rock-arm, and a spring for turning said arm in one direction, said operating means being adapted to turn said rock arm in the opposite direction.

3. A barber chair comprising a seat supporting part, a cylinder in which said seat supporting part is rotatably mounted, a clamp for fixing said seat supporting part against rotation in said cylinder, means for operating said clamp, said clamp comprising a rock arm, a screw shaft operated by said rock-arm, a spring for turning said arm in one direction, said operating means being adapted to turn said rock arm in the opposite direction, and adjustable means at one end of said spring for adjusting the tension thereof.

4. A barber chair comprising a seat supporting part, a cylinder in which said seat supporting part is rotatably mounted, a clamp for fixing said seat supporting part against rotation in said cylinder, means for operating said clamp, said clamp comprising a rock arm, a screw-shaft actuated by said rock arm, a spring adapted to rock said rock arm in a direction to turn said screw-shaft to exert binding pressure, said means for operating said clamp comprising a link attached to the other end of said rock arm and adapted to turn said rock arm in a direction to turn said screw-shaft to a releasing position.

5. A barber chair comprising a rod adapted to be connected to a reclinable back and foot rest, and a clamp for holding said rod, said clamp comprising a mount therefor, sleeve and a clamping part slidable in said sleeve screw-threaded in said mount.

6. A barber chair comprising a rod adapted to be connected to a reclinable back

and foot rest, and a clamp for holding said rod, a sleeve, a clamping part slidably mounted in said sleeve, and a sleeve rotatable around said first sleeve acting as a guide for said back and foot rest rod.

70

7. A barber chair comprising a rod adapted to be connected to a reclinable back and foot rest, and a clamp for holding said rod, said clamp comprising a pair of adjustable sleeves, one on each side of said rod, a clamping part slidable in said sleeves, and a spring for pressing said clamping part against said rod.

8. A barber chair comprising a rod adapted to be connected to a reclinable back and foot rest, and a clamp for holding said rod, said clamp comprising a sleeve, a clamping part slidable in said sleeve, a spring for pressing said clamping part against said rod, and an adjustable sleeve for adjusting the tension of said spring.

9. A barber chair comprising a rod adapted to be connected to a reclinable back and foot rest, and a clamp for holding said rod, said clamp comprising a rotatable sleeve having sharpened edges adapted to bear against said back and foot rest rod, said sleeve being rotatable to bring new portions of its sharpened edge against said rod, when portions of the sharpened edge become dulled.

10. A barber chair comprising a rod adapted to be connected to a reclinable back and foot rest, and a clamp for holding said rod, said clamp comprising a pair of sleeves, a clamping part slidable in said sleeves, a rotatable sleeve surrounding said first-named sleeves and acting as a guide for said back and foot rest rod, a spring for pressing said clamping part against said back and foot rest rod, and a lever for pressing said clamping part against the pressure of its spring to release said back and foot rest rod from said clamp.

11. A barber chair comprising a rod adapted to be connected to a reclinable back and foot rest, a clamp for holding said rod, a rock shaft, a cam on said rock shaft adapted to move said rock shaft axially, when rocked, and a connection between said rock shaft and said clamp, said rock shaft by its axial movement operating said clamp to release said rod.

12. A barber chair comprising a rod adapted to be connected to a reclinable back and foot rest, a clamp for holding said rod, a rock shaft, a cam on said rock shaft adapted to move said rock shaft axially when rocked, a connection between said rock shaft and said clamp, said rock shaft by its axial movement operating said clamp to release said rod, and means for limiting the rocking movement of said rock shaft.

13. A barber chair comprising a rod adapted to be connected to a reclinable back

130

and foot rest, a clamp for holding said rod, a rock shaft, a cam on said rock shaft adapted to move said rock shaft axially, a connection between said rock shaft and said clamp, said rock shaft by its axial movement operating said clamp to release said rod, said cam having a notch therein, and a fixed part having a part coacting with said notch in said cam for limiting the rocking movement of said rock shaft.

14. A barber chair comprising a rod adapted to be connected to a reclinable back and foot rest, and a clamp for holding said rod, said clamp comprising a slidable clamping part, a rotatable sleeve, a lever for operating said clamping part, and means for operating said lever, said lever having a swiveled connection with said rotatable sleeve, and a connection with said lever operating means.

15. A barber chair comprising a rod adapted to be connected to a reclinable back and foot rest, and a clamp for holding said rod, said clamp comprising a slidable clamping part, a rotatable sleeve, a lever for operating said clamping part, said lever having a swiveled connection with said rotatable sleeve, and means for operating said lever, said means comprising a rock shaft, and a sleeve loose upon said rock shaft to which said lever is connected.

16. A barber chair comprising a rod adapted to be connected to a reclinable back and foot rest, and a clamp for holding said rod, said clamp comprising a clamping part, a lever for operating said part, a rock shaft, a sleeve on said rock shaft to which said lever is connected, and means for imparting axial movement to said rock shaft and sleeve, said means comprising a cam.

17. A barber chair comprising a rod adapted to be connected to a reclinable back and foot rest, and a clamp for holding said rod, a rotatable seat supporting part and means for fixing said seat supporting part against turning, means for operating said clamping means and said fixed means, said means comprising a rock shaft, a sleeve on said rock shaft, a connection between said sleeve and clamping means and a cam for axially moving said sleeve to operate said clamp, and means operated by a rocking movement of said rock shaft to operate said fixing means.

18. A barber chair comprising a seat supporting part, a cylinder in which said seat supporting part is rotatably mounted, a clamp for fixing said seat supporting part against rotation in said cylinder, said clamp comprising a rock-arm and a screw-shaft operated by said rock-arm, and means for operating said clamp comprising a lever, a rock shaft and a projection on said rock shaft, said projection operating said lever to operate said clamp.

19. A barber chair comprising a seat supporting part, a cylinder in which said seat supporting part is rotatably mounted, a clamp for fixing said seat supporting part against rotation in said cylinder, a lever for operating said clamp, a rock shaft, and a projection on said rock shaft, said projection operating said lever to operate said clamp, said lever having a recess adapted to receive said projection in a predetermined position of said projection.

20. A barber chair comprising a seat supporting part, a cylinder in which said seat supporting part is rotatably mounted, a clamp for fixing said seat supporting part against rotation in said cylinder, a lever for operating said clamp, a rock shaft, and a projection on said rock shaft, said projection operating said lever to operate said clamp, said projection being adjustable around the axis of said rock shaft.

21. A barber chair comprising a seat supporting part, a cylinder within which said seat supporting part is mounted, a base for supporting said cylinder, said base comprising a base plate and two surrounding parts, and means for fastening together said base plate and surrounding parts, said means comprising a resilient tie piece adapted to be connected to said part and to said base plate.

22. A barber chair comprising a seat supporting part, a cylinder within which said seat supporting part is mounted, a base for supporting said cylinder, said base comprising a base plate and two surrounding parts, and means for fastening together said base plate, surrounding parts, and said cylinder, said means comprising lugs, said surrounding part overhanging parts of said cylinder, and a resilient tie piece connected to said surrounding part and to said base plate.

23. A barber chair comprising a rod adapted to be connected to a reclinable back and foot rest, and a clamp for holding said rod, said clamp comprising a clamping part, a rotatable, axially adjustable sleeve, a lever for operating said clamping part, said lever having a swiveled connection with said sleeve, and means for operating said lever, said sleeve being adjustable to vary the extent of movement of said operating means on said lever to operate said clamping part.

24. A barber chair comprising a seat-supporting part, a cylinder in which said seat-supporting part is rotatably mounted, a clamp for fixing said seat-supporting part against rotation in said cylinder, said clamp comprising a rock-arm, a screw-shaft operated by said rock-arm, and a piece having an angular movement into binding contact with said cylinder operated by said screw-shaft, and means for operating said clamp.

25. A barber chair comprising a rod adapted to be connected to a reclinable back and foot rest, and a clamp for holding said

rod, said clamp comprising a slidable clamping part, a lever for operating said clamping part, and means for operating said lever, said means comprising an axially movable 5 rock shaft and connections between said rock shaft and lever.

26. A barber chair comprising a rod adapted to be connected to a reclinable back and foot rest, and a clamp for holding said 10 rod, a rotatable seat-supporting part, and means for fixing said seat-supporting part against turning, means for operating said clamping means and said fixing means, said means comprising a rock shaft, a connection 15 between said rock shaft and clamping means, means for axially moving said rock shaft to operate said clamp, and means operated by

a rocking movement of said rock shaft to operate said fixing means.

27. A barber chair comprising a rod 20 adapted to be connected to a reclinable back and foot rest, a clamp for holding said rod, and means for operating said clamp, said means comprising a rock shaft, a cam for axially moving said rock shaft when rocked, 25 a spring pressing axially on said rock shaft, and adapted to cause the rock shaft to turn to an initial position when said rock shaft is released, and a connection between said rock shaft and clamp. 30

In witness whereof, I have hereunto signed my name.

GIUSEPPE CARMELO LARAIA.
